UNITED STATES PATENT OFFICE.

EARL T. BENNINGTON, OF CLEVELAND HEIGHTS, OHIO, ASSIGNOR TO THE CLEVELAND CRANE & ENGINEERING COMPANY, OF WICKLIFFE, OHIO, A CORPORATION OF OHIO.

DROP TRACK SECTION.

Application filed November 28, 1924. Serial No. 752,685.

To all whom it may concern:

Be it known that I, EARL T. BENNINGTON, a citizen of the United States, residing at Cleveland Heights, in the county of Cuyahoga and State of Ohio, have invented a certain new and useful Improvement in Drop Track Sections, of which the following is a full, clear, and exact description.

This invention relates to a drop track section for overhead carrier tramrail systems which is adapted to receive a carrier from a fixed section of a track and be lowered with the carrier thereon.

An object of the present invention is to provide improved means for automatically stopping and positioning the drop track section in alignment with the fixed track.

More particularly, the present invention aims to provide in connection with a drop track section, suspended by hoist cables, means for properly positioning the drop track section as it approaches the fixed track and for instantly stopping the drop track section in alignment with the fixed track without excessive shock to the hoisting mechanism.

A further object is to provide automatically operated means for blocking the ends of the fixed track adjacent the drop track section whenever the drop track section is moved out of alignment with the fixed track to prevent carriers running into the gap formed when the drop track section is lowered, the locking means being moved to inoperative position when the drop track section is returned into alignment with the fixed track and further to provide automatically operated means on the drop track section for holding a carrier thereon whenever the section is lowered out of alignment with the fixed track, the releasing means on the drop track section being released whenever the track section is returned into alignment with the fixed track.

With the above and other objects in view the invention may be said to comprise the device as illustrated in the accompanying drawing hereinafter described and particularly set forth in the appended claims, together with such variations and modifications thereof as will be apparent to one skilled in the art to which the invention appertains.

Reference should be had to the accompanying drawings forming a part of this

specification in which Fig. 1 is a side elevation of the drop track section and adjacent portions of the fixed track; Fig. 2 is a vertical transverse section taken through the drop track section; Fig. 3 is a vertical sectional detailed view showing the resilient connection interposed between each of the hoist cables and the drop track section.

In the accompanying drawings, the invention is illustrated as applied to a monorail track having spaced fixed rail portions 1 and a vertically movable rail section 2 which is adapted when in its uppermost position to bridge the gap between the fixed rails 1 in order to properly position the movable rail section, the ends 1^a of the fixed rails 1 are tapered to engage the tapered ends 2^a of the rail 2, the rails 1 being T-shaped in cross-section and the rail 2 being in the form of an I-beam of considerably greater height than the rails 1, the rails 1 having base flanges 1^b over which the wheels of the carriers run and the rail 2 having base flanges 2^b which when the rail 2 is in its uppermost position, align with the flanges 1^b of the main track so that carriers can run across the drop track section. The ends of the fixed track 1 adjacent the gap in which the drop track section is located, are supported from an overhead frame comprising a pair of spaced channel bars 4 which are arranged back to back and extend across the gap between the fixed track sections 1, the channel bars 4 being suspended by angle suspension bars 5 which depend from an overhead support 6 and the ends of the rails 1 being supported by hanger posts 7 which are secured at their upper ends between the ends of the bars 4 and at their lower ends to the webs of the T-rails 1. The drop section 2 is suspended by hoist cables 8 which extend upwardly from opposite ends thereof over sheaves 9 carried by brackets 10 secured to the supports 6 and thence to suitable winding drums. The hoist cables 8 extend downwardly between the channel bars 4 and associated with the hoist cables are pilot guides which serve to accurately position the drop section 2 in alignment with the fixed track 1. The pilot guides comprise upwardly converging socket members 11 secured between the bars 4 and upwardly extending tapered projections 12 secured to the top of the drop section 2, the cables 8 being secured to the projections 12 and extending upward-

100
105
110

ly therefrom through the hollow socket members 11 so that as the drop track section is elevated by the cables the projections 12 will enter the socket members 11. The tapered projections 12 may be provided with external grooves 12^a which cooperate with corresponding internal ribs 11^a within the socket members 11. The cooperating pilot guides 11 and 12 serve to accurately position the drop section 2 in alignment with the fixed track 1, the projections 12 and sockets 11 being so positioned that when the projections 12 are in full engagement with the sockets 11 the flanges 2^b of the drop track section align with the flanges 1^b of the fixed track. The proper positioning of the drop track section is also facilitated by the tapered ends 1^a and 2^a of the fixed track and drop track section, the inwardly inclined ends 2^a of the drop track section engaging with the correspondingly inclined ends 1^a of the fixed track sections to guide the drop track section into aligning position.

The socket members 11 form fixed stops which act to instantaneously stop the drop track section in a position in which it aligns the fixed track and, to avoid undue shock to the hoisting mechanism, resilient connections are provided between the hoist cables 8 and the drop track section. The tapered projections 12 are hollow and have openings 13 in their upper ends through which the cables 8 extend, the lower ends of the cables having a sleeve 14 attached thereto upon which are mounted washers 15 which are supported by nuts 16 upon the lower ends of the sleeves 14 and a compressing coil spring 17 being interposed between the washer 15 of each of the cables and the upper end of the hollow projection 12. The lower end portions of the cables and the spring supporting attachment thereon preferably project through openings in the top of the section 2 and the web of the I-beam rail section is cut away at 18 to accommodate the lower end of the cable attachment. The cable operating mechanism is preferably operated by an electric motor which is controlled by a limit switch having an arm 19 carrying a roller 19^a supported upon the underside of the channel bars 4 and positioned to be engaged by the top of the drop section 2 as the drop section approaches its upper limit of movement, the drop section being carried upwardly a short distance after the opening of the switch by its own momentum. After the drop track section has been brought to a sudden stop by engagement of the projections 12 in the socket members 11, the hoisting mechanism will be permitted to have a slight additional movement by reason of the yielding connection between the lower ends of the cable and the drop track section which will prevent injury to the hoisting mechanism such as

might be occasioned by sudden stopping thereof.

It is desirable that means be provided for preventing carriers from running off the ends of the fixed track section into the opening formed when the drop track section is lowered and to accomplish this result there is a stop member in the form of a T-bar 20 slidably mounted upon the inner face of each of the hanger posts 7. The base of each T-bar stop 20 rests against the face of the posts 7 and the bars are guided for vertical sliding movement by means of guide plates 21 secured to the posts and overlying the base flanges of the bars 20. The webs 20^a of the stop bars 20 project inwardly beyond the ends of the fixed rails 1 and are positioned in the path of movement of the drop section 2. When the drop track section is lowered the stop bars 20 are held by gravity in engagement with the tops of the rails 1 and will be engaged by the wheels of a carrier, thus preventing the carrier from running off the end of a track. When the drop track section is elevated the ends thereof, as the section approaches its uppermost position in alignment with the rails 1, engage the projecting webs 20^a of the stop bars 20 and raise the stop bars to a position clear of the wheels of carriers traveling on the tracks so that carriers may pass from the fixed track sections 1 to the drop track section.

Means are also provided for automatically retaining a carrier upon the drop track section after the drop track section has been lowered and this means consists of a pair of pivoted gravity actuated stop bars 22 at each end of the section 2. The bars 22 of each pair are pivoted on longitudinally disposed pivot pins mounted upon the top of the section 2 and below the pivot. Each of the bars is bent outwardly and downwardly and provided with a widened lower end portion 22^a which is normally held by gravity close to the web of the rail section 2 and in the path of movement of carrier wheels resting upon the flanges 2^b. Above the pivot 23 each of the arms 22 has an upwardly and outwardly inclined portion 22^b which extends to the opposite side of the pivot from the wheel engaging portion 22^a, the bars 22 of each pair being disposed in crossed relation. As the drop section 2 approaches its uppermost position the extending arms 22^b of the pivoted stop bars engage with the fixed channel bars 4 and are pushed downwardly with respect to the section 2 causing the wheel blocking portion 22^a to swing outwardly far enough to clear the wheels of the carriers. When the drop track section is lowered out of alignment with the fixed track the arms 22 are moved out of engagement with the fixed bars 4 permitting the blocking portion 22^a to swing

by gravity into wheel blocking position, this movement being assisted by a spring 24 connecting the arms beneath the pivot.

Having described my invention, I claim—

- 5 1. In a device of the character described, a track having a gap therein, a fixed member above the gap, a drop track section adapted when in its uppermost position to bridge the gap, and interfitting tapered 70 projections and sockets on the track section and fixed member for aligning the drop track section with the fixed track.
- 10 2. In a device of the character described, a fixed track, a drop track section movable 75 into and out of alignment therewith, fixed tapered socket members above the drop track section, tapered projections on the drop track section adapted to fit in said sockets, and hoist cables passing through said sockets and attached to said projections, said sockets cooperating with the projections to align the drop track section with the fixed track.
- 15 3. In a device of the character described, a fixed track having a gap therein, a fixed member above the gap, tapered sockets carried by the fixed member, a drop track section adapted when in its uppermost position to bridge the gap and having tapered 80 projections adapted to fit in the sockets, and hoist cables extending through the sockets and connected to the projections.
- 20 4. In a device of the character described, a fixed track having a gap therein, a drop track section adapted when in its uppermost position to bridge said gap, a fixed stop 85 in the path of movement of the drop track section and adapted to stop the same in alignment with the fixed track, and hoisting mechanism having a yieldable connection to the drop track section adapted to absorb the momentum of the hoisting mechanism upon engagement of the drop track section with the fixed stop.
- 25 5. In a device of the character described, a fixed track having a gap therein, a drop track section adapted when in its uppermost position to bridge said gap, a fixed stop 90 in position to be engaged by the drop track section in its upward movement, and adapted to stop the same in alignment with the fixed track, and motor operated hoisting mechanism including a suspension cable having a resilient connection to said drop track section adapted to absorb the momentum of the hoisting mechanism upon engagement of the drop track section with the fixed stop.
- 30 6. In a device of the character described, a fixed track, a drop track section adapted 95 when in its uppermost position to align with the fixed track, a rigidly supported member above the drop track section, upwardly tapering socket members fixed to the rigid member, tapering projections fixed to the
- drop track section and projecting upwardly therefrom, said projections being engageable in said sockets to position the drop track section in alignment with the fixed track and having a cable receiving opening, hoist cables depending vertically through the socket members and through the opening of the hollow projections, supporting members attached to the lower ends of the cables, and compression springs interposed between the 100 said supporting members and the drop track section.
7. In a device of the character described, a fixed track having a gap therein, a drop track section adapted when in its uppermost position to bridge the gap in the fixed track, hoisting means connected to the drop track section, a fixed frame above the gap and extending across the same, posts connecting said frame to the fixed track, vertically 105 slideable stop members for blocking the fixed track mounted on the posts and having parts projecting into the gap and adapted to be engaged and lifted out of operative position by the drop track section as it approaches its uppermost position, pivoted stop members at the ends of the drop track section which are normally held in blocking position, said pivoted stop members having parts engageable with the fixed frame as the drop track section approaches its uppermost position to shift the same to inoperative position.
8. In a device of the character described, a track having a gap therein, a drop track section adapted when in its uppermost position to bridge the gap in the fixed track, hoisting means connected to the drop track section, a fixed frame above the gap and 110 extending across the same, posts connecting said frame to the fixed track, vertically slideable stop members for blocking the fixed track mounted on said posts and having portions projecting into the gap and adapted to be engaged and lifted out of operative position by the drop track section as it approaches its uppermost position.
9. In a device of the character described, a monorail track having a gap therein, a drop track section adapted when in its uppermost position to bridge the gap, a fixed member above the track and extending longitudinally thereof over the gap, hoisting means connected to the drop track section, and a pair of stop members on the drop track section engageable with carrier wheels on opposite sides thereof, said stop members being pivoted to swing about an axis parallel with the track section and having portions below the pivots movable into and out of the path of the carrier wheels and portions above the pivots engageable with the fixed member.
10. In a device of the character described, a monorail track having a gap therein, a 115

- 4
- 5 drop track section adapted when in its uppermost position to bridge the gap, a pair of stop members on the drop track section pivoted to swing about a pivot parallel with the longitudinal axis of the track section and directly above the same, said members having downwardly extending portions movable toward and from opposite sides of the track section into and out of the path of
- 10 the carrier on the said track section, each stop member having a part extending upwardly from the pivot and outwardly from the pivot, the upwardly and downwardly extending portions of each stop member being upon opposite sides of the pivot, a fixed member above the gap in a position to be engaged by the upwardly extending portions of the stop members to shift the stop members out of carrier engaging position as the
- 15 drop track section approaches its uppermost position, and means for raising and lowering the drop track section.
11. In a device of the character described, a track having a gap therein, a drop track
- 20 section adapted when in its uppermost position to bridge the gap, hoisting means for raising and lowering the drop track section, a fixed stop with which the drop track section engages to position the same in alignment with the fixed track, and means for controlling the hoisting means including a limit switch adapted to be opened by the drop track section prior to its engagement with the stop member.
- 25 12. In a device of the character described, a fixed track having a gap therein, a drop track section adapted when in its uppermost position to bridge said gap, a fixed stop in the path of movement of the drop
- 30 track section and adapted to stop the same
- 35 in alignment with the fixed track, and hoisting mechanism for the drop track section including a suspension cable, an electric motor for driving said mechanism and a limit switch for the motor so positioned as to be actuated by the drop track section prior to the engagement of said section with the fixed stop.
- 40 13. In a device of the character described, a fixed track having a gap therein, a drop track section adapted when in its uppermost position to bridge said gap, a fixed stop in the path of movement of the drop track section and adapted to stop the same in alignment with the fixed track, hoisting mechanism for the drop track section including a suspension cable, an electric motor for driving said mechanism and a limit switch for the motor so positioned as to be actuated by the drop track section prior to the engagement of said section with the fixed stop, and a spring connection between said suspension cable and drop track section adapted to absorb the momentum of the hoisting mechanism.
- 45 14. In a device of the character described, a fixed track having a gap therein, a drop track section adapted when in its uppermost position to bridge said gap, hoisting mechanism for the drop track section including a suspension cable, and means to operate the cable, and means for limiting swinging movements of the cable comprising a fixed member over the gap and adjacent thereto, said member having a restricted opening through which the cable passes.
